NASAL APPLICATOR

Charles S. McGivern, Margate City, N. J.

Application January 21, 1944, Serial No. 519,171

1. Claim. (Cl. 128—260)

This invention relates to a nasal applicator. Nasal applicators in common use today by the medical profession fall generally in two classifications, i. e., disposable applicators and non-disposable applicators. Non-disposable applicators are used over and over again, and sterilized between each use. The original cost of non-disposable nasal applicators has, in the past, been relatively high. However, if they had been constructed so that long continued use was possible, the over all cost would have been much cheaper than disposable applicators. Non-disposable applicators used in the past have been made from metal and have had a handle bonded thereto. While handles are very desirable from the physician's standpoint, they have created many serious problems. In the first place, the handles which have been bonded to the shank of the applicators have been relatively heavy, in many instances being heavier than the shank of the applicator. Obviously, such construction has been undesirable from the patient's standpoint by causing undue pressure of the cotton on the nasal passage. Also, the weight of the handle on non-disposable applicators made in the past has often dislodged the medicant bearing cotton from the position originally placed by the physician, thereby defeating the intended function of the medicant. Furthermore, the handles bonded to non-disposable nasal applicators constructed in the past have, after long continued usage and sterilization, become loose and finally separated from the shank of the applicator, thereby rendering the applicator valueless because of the cost of rebonding the handle to the shank has been prohibitive.

Because of the aforementioned problems of the usual non-disposable nasal applicators, physicians and the trade have resorted to disposable applicators. The disposable applicators now commonly in use by physicians consists merely of an elongated slender shank of wood. This type of applicator is now almost universally used by physicians because the original cost is small, it is light in weight so that it causes the least amount of discomfort to the patient, and it will not tend to dislodge the medicant bearing cotton from the position originally placed by the physician. However, they do not have a handle and thus, it is difficult for the physician to readily grasp the same. Furthermore, they can be used only once because they are not susceptible to sterilization. Therefore, while their original cost is small, a physician will, over a long period of time,

use a great number of them, thus making the cost of nasal applicators to the physician relatively high.

One of the prime objects of my invention is to provide a nasal applicator having a handle wherein the applicator may be used indefinitely without danger of the handle becoming separated from the same.

Another prime object of my invention is to provide a nasal applicator having a handle wherein the handle is relatively light in weight.

Another prime object is to provide a nasal applicator wherein the cotton may be easily and quickly secured thereto without danger of the cotton accidentally separating therefrom.

Another object of my invention is to provide a nasal applicator wherein the aforementioned objects are maintained and which can be made for a fraction of the cost of prior non-disposable nasal applicators.

In order to fully understand my invention, reference is now made to the drawing, in which:

Figure 1 is a side elevation of the applicator having cotton shown in outline, secured to one end thereof;

Figure 2 is a top plan view of the applicator; and

Figure 3 is a bottom plan view of the applicator;

Figure 4 is an enlarged fragmentary side view of the applicator.

Reference numeral 10 indicates the shank of the nasal applicator and is made of a non-corrosive acid resistant metal, preferably sterling silver wire of suitable gauge. It will be understood, of course, that other suitable metal may be used which is not subject to corrosion and which would not be attacked by the acids and other medicants used by a physician. I have found, however, that sterling wire lends itself admirably to this purpose. A handle, generally indicated at 12 is formed integrally with the shank 10 by bending the wire adjacent one end thereof over on the shank at 14, after which the wire is bent around the shank to form a plurality of convolutions. It will be noted that the convolution on the outer end of the handle is larger in diameter than the next convolution, and so on, so that the convolutions gradually decrease in diameter until the inner convolution frictionally engages the outer periphery of the shank 10. It will also be noted that the convolutions 16 are widely separated to form an elongated handle which may be easily and securely grasped by the physician between his forefinger and thumb. While the space between the convolutions and their diameter is, of

course, not critical, it will be understood that the diameter of the convolutions and the space therebetween should be sufficiently great to provide a handle of suitable size which does not materially add to the weight of the applicator. In actual practice, I have found that the most desirable length of a nasal applicator is approximately six inches. Therefore, it would be desirable to start with a piece of sterling wire approximately nine inches long, and bend approximately three inches of one end thereof to form the convolutions as shown in Figure 1. Five convolutions should normally be sufficient to form a handle of approximately one-fourth inch in diameter and approximately one inch in length. Thus, the handle, if formed as shown in Figure 1, will be of sufficient diameter and length, and will make the applicator only approximately a third heavier in total weight than a six inch applicator would be without a handle.

Another important aspect of the handle which should be noted is that the innermost convolution is crimped about the periphery of the shank 10 and frictionally held in position thereon so that the other convolutions will remain in their properly spaced positions about the shank.

At the end of the shank 10 opposed to the handle 12, I have formed an integral projection 18 so that the cotton, when wound about the shank 10, will be firmly secured thereto. While the projection may take any suitable form, I prefer to make the same in the wedge-shape shown (it being slightly enlarged in the drawing for purposes of clarity) by flattening the tip portion of the shank. By providing the base of the wedge at the outer extremity of the shank, it will be obvious that the cotton will not accidentally separate from the applicator.

A groove 19 is formed in the shank 10 to serve as indicia for indicating to the physician the amount of cotton to be wrapped about the applicator. Also, I have provided serrations 20 which extend about the periphery of the shank 10, and extend from the indicia groove 19 downwardly for a short distance. The serrations 20 will enable the physician to wrap the cotton tightly at the inner portion thereof. Thus, with the serrations 20 securing the cotton at its inner portion to the shank 10, and the projection 18 securing the cotton at its outer portion to the

shank, the possibility of having the cotton accidentally separate from the applicator is quite remote. Furthermore, by having an indicia groove positioned immediately above the serrations, the physician will spread the cotton out to the desired length. Obviously if the physician used only a small dob of cotton at the end of the applicator, the cotton might work loose while in the nasal passages. It is well known in the medical profession that cotton is too often lost in the nasal passages because of separation of the cotton from the applicator. When the cotton is lost, the physician must resort to probing, and too often surgery must be performed in order to remove the cotton. Thus, by providing the projection 18, the serrations 20, and spreading the cotton out in length to the indicia groove 19, I have found that it is impossible to have the cotton accidentally separate from the applicator, while, at the same time, it is exceedingly easy to remove the cotton from the applicator when it is so desired.

From the foregoing description, it will be understood that the nasal applicator which forms the subject-matter of this invention is a unitary integral structure having a handle which cannot possibly work loose and wherein the handle is light in weight (not adding more than one-third to the total weight of the applicator), and wherein the cotton will not accidentally become separated from the applicator.

I claim:

A nasal applicator comprising an elongated shank, a handle positioned adjacent one end of said shank and being formed of a plurality of spaced convolutions which encircle said shank, the innermost convolution frictionally binding said shank for preventing movement of said convolutions relative to each other and said shank, said convolutions being formed integrally with said shank, said handle, in its entirety, being of a weight less than said shank and said projection a projection formed integrally with said shank and positioned adjacent the other end of said shank, serrations on said shank adjacent to but separated from said projection, and indicia on said shank positioned between said handle and said serrations.
